[57] **CLAIM**

The ornamental design for a hand-held tool, as shown.

DESCRIPTION

FIG. 1 is a left-front side perspective view of a hand-held tool showing my new design;

FIG. 2 is a front elevational view;

FIG. 3 is a left side elevational view;

FIG. 4 is a rear elevational view;

FIG. 5 is a right side elevational view;

FIG. 6 is a top plan view; and

FIG. 7 is a bottom plan view thereof.

The broken line showing of the plug is for illustrative purposes only and forms no part of the claimed design.
